INVENTOR.

UNITED STATES PATENT OFFICE.

JOHN P. BROPHY, OF CLEVELAND HEIGHTS, OHIO.

STOCK REST FOR LATHES AND LIKE MACHINES.

Application filed June 5, 1922. Serial No. 566,014.

To all whom it may concern:

Be it known that I, JOHN P. BROPHY, a citizen of the United States, and a resident of Cleveland Heights, county of Cuyahoga, and State of Ohio, have invented a new and useful Improvement in Stock Rests for Lathes and like Machines, of which the following is a specification, the principle of the invention being herein explained, and 10 the best mode in which I have contemplated applying that principle, so as to distinguish it from other inventions.

The present improvements relating, as indicated, to stock rests have more particular regard to rests for supporting bars or rods that are being fed into automatic screw machines, lathes, either single or multiple spindle, and like machines. It is well known that the feeding of the stock 20 to machines of the class in question is an extremely noisy operation, particularly where a plurality of spindles are carried in a rotatable indexing head, although the rotation of the individual rods incidentally to 25 certain operations performed thereon in the machines creates a great amount of clatter with the result that a shop equipped with such machines is extremely noisy.

The object of the present invention, accordingly, is the provision of a stock rest for use in the connection stated whereby most of the noise will be eliminated without in any way interfering with the forward feeding movement of the individual 30 pieces or the rotation thereof either individually or altogether as where an indexing stock spindle head is employed. To the accomplishment of the foregoing and related ends, the invention, then, consists of the 35 means hereinafter fully described and particularly pointed out in the claims, the annexed drawing and the following description setting forth in detail certain mechanism embodying the invention, such disclosed means constituting, however, but one 40 of various mechanical forms in which the principle of the invention may be used.

In said annexed drawing:-

Fig. 1 is a side elevation of my improved 45 stock rest as designed for a multiple spindle

machine in which the pieces of stock require to be rotatable as a body as well as individually; Fig. 2 is an end elevation of such stock rest, as viewed from the left in Fig. 1; Figs. 3 and 4 are, respectively, a 55 central longitudinal section of said rest and a transverse section thereof, the plane of the latter being indicated by the line 4—4, Fig. 1; Fig. 5 is a sectional view similar to that of Fig. 3, but illustrating a modification in construction; and Fig. 6 is another sectional view similar to that of Fig. 3, but illustrating a construction adapted for a single spindle machine.

A plurality of stands 1, preferably two 65 in number, as shown in Fig. 1, will be employed to support my improved noiseless or muffled stock rest, such stands being aligned with the axis of the automatic screw machine, lathe, or like machine, of which the 70 rear end of the head 2 only is shown (see Fig. 1). In such head, as will be understood, are mounted suitable spindles (not shown) carrying the stock feed tubes 3 and the usual chucks or equivalent stock gripping means (also not shown), which are individually rotatable about their respective axes, in order to turn the stock against a fixed tool. Tubes 3 are reciprocable in a 75 longitudinal direction in order to feed the stock forward from time to time the same being of well known construction in metal working machines.

The central element of the stock rest, where a plurality of guides require to be 80 provided for a corresponding number of bars or rods *a*, is a tubular shaft 5 of a length sufficient to span the distance between the stands 1; and the end of said shaft adjacent the machine head 2 is operatively connected with the latter through an extension 6 fixedly attached to a central point on said head, the connection with the shaft being preferably on the order of a flexible or universal coupling 7. In order to 85 insure the accurate alignment of the rods or bars *a* with the stock feed tubes 3, a disk 8, provided with properly spaced openings 9, is slidably mounted on said shaft 90 extension 6, being held in desired longi-

tudinal position thereon by means of a set screw 10. Normally when the stock rest is in use, said disk will be located, as shown in full lines in Fig. 1, as far forward as possible and yet not interfere with the tubes when retracted in their stock feeding movement. However, when it is desired to entirely remove said tubes, as in setting the machine for operation on a different gauge 10 of stock, the disk may be moved back to the position indicated in dotted outline. As shown in Fig. 3, the openings 9 are larger in diameter than the bars or rods and are provided with bushings 11 of 15 leather, fiber or composition that more closely fit such stock and at the same time prevent any metal-to-metal contact with such disk.

The stock guides in the main body of the 20 rest are preferably divided longitudinally into two sections, where the distance between the stands 1, 1, is considerable, although it will be understood that a single such section of necessary length may be substituted. 25 These guides consist of metal tubes 12 held at their ends in disks 13 similar to disk 8, the apertures 14 in which such tubes are thus fitted corresponding of course in location with apertures 9 in such last mentioned disk. Tubes 12 are furthermore provided at their respective ends with interior bushings 15 of the same character as the bushings 11 in said disk 8. The disks 13 at the respective ends of the stock rest serve to 30 support the latter by slidably resting on transversely spaced flanged rollers 16 mounted on the upper ends of the corresponding stands 1, as best shown in Figs. 2 and 4. Said stock rest is accordingly rotatable as 35 a whole with a minimum of frictional resistance whenever the index movement of the machine head 2 is imparted to said rest through the connecting shaft extension 6.

Between each pair of disks 13, marking 40 the respective ends of the sections of the stock rest, the guide tubes 12 are enclosed by a cylindrical casing 16, preferably of sheet iron, and the space within such casing or shell not occupied by the tubes or the central shaft 5 is filled with a sound-proof or sound insulating packing 17. Any of the usual materials, such as mineral wool for example, employed in sound-proofing floors and walls may be used for such packing and 45 as a result the noise which would otherwise be produced upon rotation of the rods or bars in the guide tubes, and upon rotation of the rest as a whole during index movement of the machine head 2, is so deadened or 50 muffled as to render the operations in question comparatively noiseless. The bushings 11 and 15 assist, of course, in deadening such noise not only by reason of the character of the material whereof they are made, but

also by tending to keep the bars or rods 65 from direct contact with the inner walls of the guide tubes 12.

In place of a disk 8 longitudinally adjustable on the shaft extension 6, whereby the stock rest is indexed, I may employ the 70 means shown in Fig. 5 for supporting the stock intermediately of the rest proper and the feed tubes 3 of the machine. Such means consist of telescoping extensions 20 slidably fitted within the corresponding guide tubes 75 12 of the stock rest. Said tubes are provided with bushings 21, similar to bushings 11 and 15 previously described, and may be extended, as shown in the upper portion of Fig. 5, so that their forward ends correspond 80 in position with the position of disk 8 shown in full lines in Fig. 1, or said tubes may be pushed back, as shown in the lower portion of Fig. 5, when it is necessary to provide clearance for the withdrawal of the 85 stock feed tubes 3 of the machine.

As shown in Fig. 6, my sound-proof construction may be just as readily adapted for use in feeding a single bar as for a plurality thereof. In such case, however, the stock 90 rest will not require to be rotatably supported on the stands 25, but the guide tube 26 will be directly mounted in the upper ends of such stands. As in the previously described construction, however, said tube 95 is enclosed by a casing 27 between which and the tube I place a sound-proof packing 28. A telescoping extension 29, similar to the one just described as being shown in Fig. 5, is employed at the forward end of 100 the rest to support the stock intermediately of the latter and the machine.

Other modes of applying the principle of my invention may be employed instead of the one explained, change being made 105 as regards the mechanism herein disclosed, provided the means stated by any of the following claims or the equivalent of such stated means be employed.

I therefore particularly point out and 110 distinctly claim as my invention:

1. In mechanism of the character described, the combination of suitable supports, a guide tube for an individual bar or rod, a shell surrounding said tube and spaced therefrom, and sound-deadening material packed between said tube and shell. 115

2. In mechanism of the character described, the combination of suitable supports, a guide tube for an individual bar or rod, a shell surrounding said tube and spaced therefrom, sound-deadening material packed between said tube and shell, and bushings of similar material interiorly fitted in the ends of said tube. 120

3. In mechanism of the character described, the combination of suitable supports, a guide tube for an individual bar or 125

rod, a shell surrounding said tube and spaced therefrom, sound-deadening material packed between said tube and shell, and a longitudinally adjustable member at the forward end of said tube for supporting the stock between the same and the machine.

4. In mechanism of the character described, the combination of two spaced supports, a disk rotatably mounted on each of said supports, a plurality of guide tubes for bar or rod stock extending at their respective ends through said disks, a shell supported at its respective ends by said disks and surrounding said tubes, and sound-deadening material packed between said tubes and shell.

5. In mechanism of the character described, the combination of two spaced supports, a disk rotatably mounted on each of said supports, a plurality of guide tubes for bar or rod stock extending at their respective ends through said disks, a shell attached at its respective ends to said disks and surrounding said tubes, sound-deadening material packed between said tubes and shell, and means for connecting one of said disks with a rotatable machine head, whereby the rest-structure inclusive of the foregoing elements may be indexed in unison with such head.

6. In mechanism of the character described, the combination of two spaced supports, a disk rotatably mounted on each of said supports, a plurality of guide tubes for bar or rod stock extending at its respective ends through said disks, a shell attached at its respective ends to said disks and surrounding said tubes, sound-deadening material packed between said tubes and shell, means for connecting one of said disks with a rotatable machine head, whereby the rest-structure inclusive of the foregoing elements may be indexed in unison with such head, and longitudinally adjustable means for supporting the stock between such last mentioned disk and such head.

7. In mechanism of the character described, the combination of two spaced supports, a disk rotatably mounted on each of said supports, a plurality of guide tubes for bar or rod stock extending at their respective ends through said disks, a shell attached at its respective ends to said disks and surrounding said tubes, sound-deadening material packed between said tubes and shell, a shaft axially aligned with one of said disks for connecting same with a rotatable machine head, whereby the rest-structure inclusive of the foregoing elements may be indexed in unison with such head, and a universal joint connecting said shaft with said disk.

8. In mechanism of the character described, the combination of two spaced sup-

ports, a disk rotatably mounted on each of said supports, a plurality of guide tubes for bar or rod stock extending at their respective ends through said disks, a shell attached at its respective ends to said disks and surrounding said tubes, sound-deadening material packed between said tubes and shell, a shaft axially aligned with one of said disks for connecting same with a rotatable machine head, whereby the rest-structure inclusive of the foregoing elements may be indexed in unison with such head, a universal joint connecting said shaft with said disk, and a disk longitudinally adjustable along said shaft and formed with openings alinged with the aforesaid guide tubes wherein the stock may be supported between said disk and machine head.

9. In mechanism of the character described, the combination of a metallic guide tube for a bar or rod of stock, bushings of sound-deadening material located in the ends of said tube, and a layer of sound-deadening material surrounding the exterior of said tube.

10. In mechanism of the character described, the combination of a stock guide tube, a shell surrounding said tube and spaced therefrom, sound-deadening material packed between the inner wall of said shell and said tube, and a second tube telescopically engaged in one end of said first named tube.

11. In mechanism of the character described, the combination of a stock guide tube, a shell surrounding said tube and spaced therefrom, a packing of sound-deadening material between said shell and said tube, a second tube slidably engaged in one end of said stock guide tube, and a bushing of sound-deadening material interiorly fitted into the outer end of said second tube.

12. In mechanism of the character described, the combination of suitably spaced supporting members, a shell rotatably carried by said members, a stock guide tube carried interiorly of said shell, and sound-deadening material surrounding said tube and spacing it from the inner wall of said shell.

13. In mechanism of the character described, the combination of a metallic stock guide tube and a layer of sound-deadening material surrounding said tube.

14. In mechanism of the character described, the combination of a stock guide tube, a layer of sound-deadening material surrounding said tube, and a longitudinally adjustable member carried at one end of said tube for supporting stock exteriorly of said tube.

15. In combination with a metal working machine having a plurality of stock feeding and rotating means, of a stock rest mounted in longitudinal alignment with said means,

said stock rest comprising a hollow cylinder, a plurality of stock carrying tubes within said cylinder, and sound-deadening material within said cylinder between the inner surface thereof and said tubes. 10

16. In mechanism of the character described, the combination of a hollow cylinder having closed ends, a plurality of stock

5 guiding tubes extending longitudinally of said cylinder and projecting through the ends thereof, and sound-insulating material within said cylinder between the inner surface thereof and said tubes.

Signed by me this 31 day of May, 1922

JOHN P. BROPHY.
